UNITED STATES PATENT OFFICE

WILLIAM SCHNELL AND FREDERICK GIUNTINI, OF DETROIT, MICHIGAN, ASSIGNORS
TO TERNSTEDT MANUFACTURING COMPANY, OF DETROIT, MICHIGAN, A COR-
PORATION OF MICHIGAN

DESIGN FOR AN AUTOMOBILE RADIATOR ORNAMENT OR SIMILAR ARTICLE

Application filed May 8, 1931. Serial No. 39,784. Term of patent 7 years.

To all whom it may concern:

Be it known that I, WILLIAM SCHNELL, a citizen of the United States, residing at 5571 Clarendon Avenue, Detroit, in the county of Wayne and State of Michigan, and I, FREDERICK GIUNTINI, a citizen of Great Britain, residing at 6335 Cartridge Avenue, Detroit, in the county of Wayne and State of Michigan have invented a new, original, and ornamental Design for an Automobile Radiator Ornament or Similar Article, of which the following is a specification, reference being made to the accompanying drawings forming part thereof.

Fig. 1 is a top plan view of an automobile radiator ornament or similar article, showing my new design;

Fig. 2 is a side elevation of the same, and Fig. 3 is a perspective of the radiator ornament turned 45° counter-clockwise from the position shown in Figs. 1 and 2.

We claim:

The ornamental design for an automobile radiator ornament or similar article substantially as shown.

WILLIAM SCHNELL.
FREDERICK GIUNTINI.
